UNITED STATES PATENT OFFICE.

BERNARD HENRY KARMEN, OF NEW YORK, N. Y.

POWDER-PUFF.

1,299,191.

Specification of Letters Patent.

Patented Apr. 1, 1919.

Application filed October 16, 1918. Serial No. 258,354.

To all whom it may concern:

Be it known that I, BERNARD HENRY KARMEN, a citizen of the United States, and a resident of the city of New York, borough of 5 Manhattan, in the county and State of New York, have invented a new and Improved Powder-Puff, of which the following is a full, clear, and exact description.

This invention relates to powder puffs, 10 and it has for its general objects to improve the construction of powder puffs of that type disclosed in United States Letters Patent 1,270,739, granted to me on the 25th day of June, 1918, the improvement residing particularly in the means for securing within 15 the body of the puff the ribbon that may form the handle of the puff or the attaching means when a ring is used as a handle.

A more specific object of the invention is 20 the employment of a suitable member, such as a ring, disk or plate of cardboard or other suitable material which lies within the upper shell or section of the powder-puff body and between which and the said shell 25 the ribbon is clamped, with the ends of the ribbon turned back under the edges of the member and held by the upsetting of the flange of that section of the body which carries the pile cloth, thus doing away with the 30 necessity of gluing the handle-forming ribbon, according to the method shown in the Letters Patent hereinbefore referred to.

With such and other objects in view, the 35 invention comprises various novel features of construction and arrangement of parts which will be set forth with particularity in the following description and claims appended hereto.

In the accompanying drawing, which 40 illustrates one embodiment of the invention and wherein similar characters of reference indicate corresponding parts in all the views,

Figure 1 is a perspective view of the 45 powder puff;

Fig. 2 is an enlarged vertical section taken centrally thereof;

Fig. 3 is a bottom plan view on a reduced scale and showing the back cloth piece and 50 the ribbon before they are turned in, and with the ribbon-holding disk in position;

Fig. 4 is a plan view of the ribbon-holding disk;

Fig. 5 is a perspective view of another form of ribbon-holding member; and 55

Fig. 6 is a perspective view of a modified form of handle.

Referring to the drawing, 1 designates the pile cloth or face of the powder puff, 2 the cloth back-piece, 3 the handle or grip, 4 and 60 5 the metal sections that form the body of the puff, and 6 the disk, or 6' the ring, that anchors the ribbon which forms the handle 3.

The peripheral edges of the cloth pieces 65 1 and 2 are clamped between the flange 7 of the cup-shaped upper section or shell 4 and the flange 8 of the section 5, which latter is in the form of a ring with an opening 9 of considerable size. The assembling of the 70 parts and the upsetting of the two sections may be done by means of special dies. Before the two parts of the body are pressed together and upset the ribbon that forms the handle 3 is looped through an opening 10 of 75 the section 4, and the ends 11 of the ribbon lie within the section 4 and between the latter and the disk or plate 6, which may be made of cardboard or other material suitable for the purpose. The extremities 12 of the 80 ribbon are turned back under the disk, as is also the marginal portion of the back cloth piece 2. While thus held the section 4 with the cloth-piece, ribbon and disk in place and the section 5 with the pile cloth in place are 85 brought together and interlocked by the dies. The dies cause the internal flange 13 of the section 5 to be pressed upwardly into conical form, whereby the ends 12 of the ribbon, together with the edges of the cloth pieces 1 90 and 2, are clamped against the disk 6, whereby the parts are firmly held in place. This method of assembling does away with the necessity of gluing the ends of the handle-forming ribbon and the parts can be assembled quickly, economically and satisfactorily. 95

The handle may be in the form of a ring 15 and ribbon 16, as shown in Fig. 6, if desired.

From the foregoing description taken in 100 connection with the accompanying drawing, the advantages of the construction and method of operation will be readily understood by those skilled in the art to which the invention appertains, and while I have described the principle of operation, together 105

with the article which I now consider to be the best embodiment thereof, I desire to have it understood that the article shown is merely illustrative and that such changes 5 may be made when desired as fall within the scope of the appended claims.

Having thus described my invention, I claim as new and desire to secure by Letters Patent:

- 10 1. A powder puff comprising a body formed of two sections compressed together in interlocking relation, a handle including a ribbon looped through one of the sections and having its ends disposed within the 15 body of the powder puff, and a disk member in the said body and under which the extremities of the ribbon are turned, the said sections having portions clamping the ribbon and disk firmly together.
- 20 2. A powder puff including a body, a member in the body, and a ribbon in the form of a loop extending out of the body and having its ends turned back over the edge of the member, said body having co- 25 operating portions for clamping the ends of the ribbon against the member.

3. A powder puff including a body formed of a pair of sections compressed together in interlocking relation, a disk in the body, and a supporting member having a portion extending out of the body acting as a handle and a portion within the body, said latter portion being clamped into frictional-holding relation with said disk by the compression of the sections of the body. 30

4. A powder puff comprising two metal sections having peripheral flanges, a back cloth piece and a pile cloth piece having their marginal portions clamped between the flanges, and the back cloth piece being 40 stretched over one section and the pile cloth piece being stretched over the other sections, the latter section being formed with an internal flange compressed inwardly toward the other section, a member disposed between 45 the sections, and a handle device including a flexible element, the ends of which are turned back under the member and clamped against the same by the last-mentioned flange. 35

BERNARD HENRY KARMEN.
